UNITED STATES PATENT OFFICE.

JOHN H. SCHROEDER, OF RUSH CITY, MINNESOTA.

BEDCLOTHES-CLAMP.

SPECIFICATION forming part of Letters Patent No. 499,855, dated June 20, 1893.

Application filed December 27, 1892. Serial No. 456,320. (No model.)

To all whom it may concern:

Be it known that I, JOHN H. SCHROEDER, a citizen of the United States, and a resident of Rush City, in the county of Chisago, and in the State of Minnesota, have invented certain new and useful Improvements in Clamps; and I do hereby declare that the following is a full, clear, and exact description thereof.

My invention has for its object to provide a clamp especially designed for use in connection with a bedstead for the purpose of keeping the bed-clothing in place upon a person while asleep, although said clamp may be employed for various purposes, such for instance as a hanger for a towel, razor-strop, hammock or other device; and the said invention consists in certain peculiarities of construction and combination of parts hereinafter described with reference to the accompanying drawings and subsequently claimed.

In the drawings Figure 1 represents a transverse section of a complete bed provided with clamps constructed according to my invention, the section being taken on line 1—1 of the succeeding figure; Fig. 2, a section taken on line 2—2 of the preceding figure, my clamp being illustrated in side elevation, and Fig. 3, a detail section taken on line 3—3 of Fig. 2.

Referring by letter to the drawings, A represents one section of my clamp in the form of a longitudinally grooved bar having perforated ears b, c, the first of these ears being for engagement with nails or screws d by which said section of the clamp may be held in place upon a suitable support. One end e of the clamp-section just described is at an angle to the remaining portion thereof and has a series of serrations upon its under side for the purpose hereinafter specified.

Pivotedly connected to the ears c and between the same is the other section B of the clamp in the form of a lever having the free end thereof provided with a perforation f pivotedly engaged by a bail C of peculiar form, this free end of the lever being at an angle approximately the same as the corresponding end of the grooved bar or stationary section A of said clamp.

The bail C above noted is in the form of two loops, one above the other, and either of these loops may be engaged with the serrations on the end e of the clamp-section A, according to the thickness of material interposed between both clamp-sections, the ten-

sion of the lever-section B being of variable 55 degree, incidental to the disposition of said bail with relation to said serrations. The grooved bar and lever sections of the clamp are cast or otherwise formed from suitable metal, and the connecting bail is made from 60 wire or such other material as may be found most desirable for the purpose.

In connection with a bedstead any desirable number of clamps may be employed, but ordinarily a set of five will be sufficient if 65 disposed as follows: one on the foot-board and two on each side-rail, upon the inner sides of said parts of the bedstead.

The bed-clothing being fastened down by the clamps it will be impossible for them to 70 be disarranged by a sleeping person no matter how restless such person may be, and consequently the latter is guarded against catching cold while asleep.

Having thus described my invention, what 75 I claim as new, and desire to secure by Letters Patent, is—

1. A clamp comprising a longitudinally grooved bar provided with perforated attaching ears and having one of its ends serrated 80 upon the under side and turned at an angle to the remaining portion thereof, a lever pivotedly connected to the other end of the bar to face the groove therein and having its free end at an angle approximate to that of the 85 serrated portion of said bar, and a bail depending from this free end of the lever, substantially as set forth.

2. A clamp comprising a longitudinally grooved bar provided with perforated attaching ears and having one of its ends serrated 90 upon the under side and turned at an angle to the remaining portion thereof, a lever pivotedly connected to the other end of the bar to face the groove therein and having its free 95 end at an angle approximate to that of the serrated portion of said bar, and a double loop bail depending from this free end of the lever, substantially as set forth.

In testimony that I claim the foregoing I 100 have hereunto set my hand, at Rush City, in the county of Chisago and State of Minnesota, in the presence of two witnesses.

JOHN H. SCHROEDER.

Witnesses:

FRANCES T. KUDERER,
FIDEL SCHMITZ.
